CLAIM

The ornamental design for a tray for a chafing pan, as shown and described.

DESCRIPTION

FIG. 1 is a top perspective view of a first embodiment of the tray of this invention;

FIG. 2 is a front view of the tray of FIG. 1, with the back view being a mirror image thereof;

FIG. 3 is a right-side view of the tray of FIG. 1, with the left-side view being a mirror image thereof;

FIG. 4 is a top view of the tray of FIG. 1;

FIG. 5 is a bottom view of the tray of FIG. 1;

FIG. 6 is a top perspective view of a second embodiment of the tray of this invention;

FIG. 7 is a front view of the tray of FIG. 6, with the back view being a mirror image thereof;

FIG. 8 is a right-side view of the tray of FIG. 6, with the left-side view being a mirror image thereof;

FIG. 9 is a top view of the tray of FIG. 6; and,

FIG. 10 is a bottom view of the tray of FIG. 6.

The broken lines show environmental structure that forms no part of the claimed design.

1 Claim, 6 Drawing Sheets
